US0D1023846S

(12) **United States Design Patent** (10) **Patent No.:** **US D1,023,846 S**
(45) **Date of Patent:** **** Apr. 23, 2024**

(54) **LATCH**

(71) Applicant: **Shenzhen Liyi Jiujiu Network Technology Co., Ltd., Guangdong (CN)**

(72) Inventor: **Xuzhong Wang, Guangdong (CN)**

(73) Assignee: **Shenzhen Liyi Jiujiu Network Technology Co., Ltd., Guangdong (CN)**

(**) Term: **15 Years**

(21) Appl. No.: **29/737,971**

(22) Filed: **Jun. 12, 2020**

(51) **LOC (14) Cl.** **12-12**

(52) **U.S. Cl.**

USPC **D12/133**

(58) **Field of Classification Search**

(57) **CLAIM**

The ornamental design for a latch, as shown and described.

DESCRIPTION

FIG. 1 is a front and right perspective view of a latch, showing my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines showing portions of the latch, form no part of the claimed design.

1 Claim, 7 Drawing Sheets
